THERMIONIC VALVE AMPLIFIER

Prafulla Kumar Chatterjee and Charles Thomas Scully, London, England, assignors, by mesne assignments, to International Standard Electric Corporation, New York, N. Y., a corporation of Delaware

Application June 22, 1943, Serial No. 491,769
In Great Britain July 23, 1942

9 Claims. (Cl. 179—171)

1

The present invention relates to low frequency amplifiers and more particularly to those adapted for direct currents. It employs, for coupling between stages, thermally sensitive resistance elements known as "Thermistors."

Thermistors have been in use for some years and are characterised by a temperature coefficient of resistance which may be either positive or negative and which is moreover many times the corresponding co-efficient for a pure metal such as copper. This property renders thermistors particularly suitable for a variety of special applications in electric circuits.

Various different materials are available for the resistance element of a thermistor, these various materials having different properties in other respects; as one example, a resistance material having a high negative temperature co-efficient of resistance comprises a mixture of manganese oxide and nickel oxide, with or without the addition of certain other metallic oxides, the mixture being suitably heat treated.

Thermistors have been employed in two different forms: (a) known as a directly heated thermistor and comprising a resistance element of the thermally sensitive resistance material provided with suitable lead-out conductors or terminals, and (b) known as an indirectly heated thermistor comprising the element (a) provided in addition with a heating coil electrically insulated from the element. A directly heated thermistor is primarily intended to be controlled by the current which flows through it and which varies the temperature and also the resistance accordingly. Such a thermistor will also be affected by the temperature of its surroundings and may therefore be used for thermostatic control and like purposes with or without direct heating by the current flowing through it. An indirectly heated thermistor is chiefly designed to be heated by a controlling current which flows through the heating coil and which will usually, but not necessarily, be different from the current which flows through the resistance element, but this type of thermistor may also be subjected to either or both the types of control applicable to a directly heated thermistor.

More detailed information on the properties of thermistors will be found in an article by G. L. Pearson in the Bell Laboratories Record, December 1940, page 106.

The object of the invention is to provide a means for coupling two stages of an electrical amplifier intended for amplifying direct current and/or low frequency currents, and overcomes the

2

disadvantages associated with direct connections between the stages, for which it is usually necessary to provide neutralising batteries or the like to deal with the steady voltage or current present

5 at the anode of a valve. The means whereby these difficulties are avoided includes the use of an indirectly heated thermistor for coupling the stages, and at the same time any necessity for separate high tension supplied or separate grid biasing sources for the various valves of the amplifier is avoided.

Another advantage of the method of the invention is that it may be easily arranged so that an amplified output signal may have its polarity 15 either the same as, or opposite to, that of the input signal, and simple switching arrangements can be provided to change the output polarity at will.

According to the invention, there is provided a 20 thermionic valve amplifier comprising a first stage and a second stage, and an indirectly heated thermistor, the resistance element of which is connected to the control grid of the second stage, the heating coil being connected in series with the 25 anode circuit of the first stage.

The invention will be more clearly understood from the following detailed description of embodiments which refer to the accompanying drawings in which—

30 Fig. 1 shows a schematic circuit diagram of a two-stage amplifier according to the invention;

Fig. 2 shows an amplifier similar to that of Fig. 1, but with alternative grid biasing arrangements;

35 Fig. 3 shows a modification of Fig. 1;

Fig. 4 shows a schematic circuit diagram of another embodiment of the invention; and

Figs. 5 and 6 show amplitude and phase change 40 characteristic curves applying to the amplifier of Fig. 4.

In this specification, all resistances not specifically referred to as thermistors are to be understood to be ordinary resistances whose values are substantially independent of the currents which 45 flow through them.

In Fig. 1 there is shown a two-stage direct current or low frequency amplifier comprising two valves V_1 and V_2 which are coupled together by means of an indirectly heated thermistor T_1 .

50 The heating coil r_1 of thermistor T_1 is connected in series with the anode circuit of the valve V_1 and the resistance element R_1 of thermistor T_1 is connected in series with a resistance R_{T_1} across a grid biasing battery GB_2 (or other suitable source). The junction point of R_1 and R_{T_1} is

connected to the control grid of valve V_2 . The anode circuit of valve V_2 is supplied from the positive high tension terminal +HT through the resistance R_7 and the output is taken directly from the anode.

The control grid of valve V_1 is biassed through the grid leak resistance R_{13} from a battery $GB1$.

If a positive potential be applied to the control grid of V_1 through the input terminal the anode current will increase, and will raise the temperature of the thermistor T_1 . If this thermistor has a negative temperature coefficient of resistance, the resistance R_1 will decrease, thereby making more negative the voltage applied to the grid of valve V_2 . This decreases the anode current of V_2 and increases the anode voltage, so that the effect of applying a positive signal to the valve V_1 is to obtain an amplified positive signal from the output terminal connected to valve V_2 . If the thermistor T_1 has a positive temperature coefficient of resistance, the reverse effect will occur, and an amplified negative signal will be obtained at the output terminal. If it should be desired to use such a thermistor and at the same time to obtain a positive output signal, the resistances R_1 and R_{t1} should be interchanged. It will be evident also that a simple switch could be provided for interchanging R_1 and R_{t1} to enable the polarity of the output signal to be reversed at will.

It will be observed that the use of the thermistor T_1 permits a common high tension source to be used for both the valves and no difficulties regarding the potentials of the cathodes are introduced. Furthermore, the two grid biassing potentials could be obtained if desired from the same source.

The amplifier shown in Fig. 1 will be useful in a number of applications where it is desired to amplify direct currents, or currents of very low frequency which are to be used to operate apparatus of various kinds. For example, an ordinary direct current measuring instrument could be connected in series with R_7 , or instead of it, or R_7 could be replaced by any network containing a measuring instrument. Alternatively, a network containing a loud speaker or a recorder or the like could be connected instead of R_7 or to the output terminals of the amplifier.

In another possible alternative arrangement the valve V_2 could be omitted and a network containing a direct current instrument or other apparatus to be operated could be connected in place of the resistance R_{t1} . In this case the thermistor T_1 controls the instrument directly without the intervention of a second valve, and the difficulties associated with the high anode voltage, and the corresponding anode current are avoided.

Fig. 2 shows an amplifier similar to that shown in Fig. 1, but provided with alternative biassing arrangements for the valves. The cathodes of V_1 and V_2 are in this case biassed positively by potentiometers R_4 , R_{14} and R_5 , R_{15} connected across the high tension supply. The thermistor resistance element R_1 is in this case connected across R_5 in series with a resistance R_6 , the control grid of V_2 being connected to the junction of R_6 and R_1 . The valve V_1 is provided with a grid leak resistance R_{16} .

When a positive signal is applied to the input terminal, the thermistor T_1 will be heated up, and assuming it to have a negative temperature coefficient of resistance the resistance R_1 will fall making the control grid of V_2 more negative to the

cathode as before, and a positive signal is obtained from the output. By interchanging R_1 and R_6 or by using a thermistor with a positive temperature coefficient, the polarity of the output signal will be reversed, and an interchanging switch can be provided if desired as explained above.

The resistances R_{14} and R_{15} could be omitted if desired, but the sensitivity of the arrangement would then be affected by variation in the cathode currents caused by the signals. It is preferable to include these resistances and to choose their values together with the values of R_4 and R_5 so that the current flowing through them is relatively large compared with the cathode currents so that the effect of the variations of the latter due to signal amplification may be negligible.

Fig. 3 shows a modification of that portion of Fig. 1 which lies between the lines XX and YY. In this case there are two thermistors T_1 and T_2 arranged in cascade so that the resistance element R_2 and T_1 is connected across the resistance R_{t1} , in series with a resistance R_{t2} . By this arrangement the potential of the control grid of valve V_2 is subjected to a double change produced by both the thermistors, whose heating coils are both in series with the anode circuit of valve V_1 ; and this process could clearly be repeated as often as desired with a corresponding increase in gain of the amplifier.

By an alternative and slightly simpler arrangement, the resistance element R_2 of the second thermistor T_2 may be simply connected in parallel with R_1 (Fig. 1), the heating coils of the second thermistor being connected in series or in parallel. The second resistor R_{t2} shown in Fig. 3 is then not necessary. In this arrangement, or in that shown in Fig. 3, the thermistors may, of course, have different characteristics.

Another embodiment of the invention is shown in Fig. 4, which represents an amplifier intended for a relatively wide band of frequencies including zero frequency, and may provide at the same time phase change correction at the low frequency end of the range. The amplifier is shown with two stages comprising respectively the valves V_3 and V_4 , but there may be any number of other stages arranged in any well known way. The two valves are shown coupled by a circuit of any type represented by the block A suitably designed for the frequencies to be amplified. The circuit A may, for example, consist of a simple resistance-capacity coupling, or a transformer, or a filter, or it may comprise any number of stages of amplification coupled in any way, and employing the same supplies as for the valves V_3 or V_4 , or different supplies.

The control grid circuit of valve V_4 is made up of two resistances R_{11} and R_{12} in series, with the resistance element R_3 of an indirectly heated thermistor T_3 connected in series with a grid biassing source $GB2$ across R_{11} .

The heating coil r_3 of the thermistor is connected in series with the anode circuit of the valve V_3 which contains also the anode resistance R_6 . The anode resistance for valve V_4 is R_{10} , and resistance R_6 is shown connecting the control grid of valve V_3 to the biassing source $GB1$ as before. The output is taken from the anode of valve V_4 .

It will be assumed that the coupling circuit A becomes inefficient towards the lower end of the frequency range, and fails altogether to transmit any direct current changes. It will be evident that the operation of the thermistor circuit in

transmitting direct current will be substantially the same as is the case of Fig. 1. Apart from the introduction of the coupling circuit A, the circuits of Figs. 1 and 4 are the same except as regards the addition of the resistance R_{12} in Fig. 4, which provides a suitable load for the circuit A, but does not effect the working of the thermistor.

When an alternating current signal is applied to the input of the amplifier shown in Fig. 4, an amplified signal will be applied to the coupling circuit A from the anode circuit of valve V_3 , and this will be transmitted to the valve V_4 in the usual way, after having been amplified (or attenuated), and suffered some phase change, according to the nature of the circuit A. This alternating current signal will also be transmitted to some extent (depending on the frequency) by the thermistor T_2 with a retardation of phase also depending on the frequency. Thus, the signal obtained from the valve V_4 will have reached this valve by both routes, the relative proportions of the signal transmitted by the two routes depending on the frequency.

The action of the circuit will be more clearly understood from the curves of Figs. 5 and 6. In Fig. 5, curve a shows the relation between the amplitude of the signal transmitted to the valve V_4 by the thermistor T_2 and the frequency, for a constant input signal. Curve b shows the corresponding curve for a suitable conventional circuit A. Curve c shows the combined effect on the valve V_4 . In Fig. 6, curves a, b and c show the corresponding phase changes. Curve a in Fig. 5 indicates that for very low frequencies the thermistor follows the current changes fairly closely, but as the frequency rises it becomes increasingly inefficient and finally ceases to transmit anything at all. Curve b indicates the usual property of most coupling circuits or amplifiers which have a progressive reduction in efficiency below some minimum frequency.

The transmission through the amplifier of Fig. 4 may be conveniently considered separately in three frequency ranges, 1, 2 and 3, as indicated in Figs. 5 and 6. In range 1, the signals are transmitted principally through the thermistor, and in range 3 through the coupling circuit. In the intermediate range 2 the signals are conveyed jointly by both means, the chief proportion being transferred progressively from the thermistor to the coupling circuit as the frequency rises. It will be understood that the regions 1, 2 and 3 will not in fact be so sharply defined as Figs. 5 and 6 indicate, these figures being intended only to be diagrammatic.

By suitably designing the thermistor T_2 , and the circuit A, the overlapping portions in the region 2 may be made to compensate, and an overall transmission curve similar to c, Fig. 5, may be obtained.

Similar considerations apply to the phase change curves of Fig. 6. In region 2 curve a indicates that the thermistor exhibits a progressively increasing lag of the phase, while curve b shows the leading phase which increases as the frequency decreases, and which is characteristic of many coupling arrangements. By suitable design, phase compensation can be obtained in region 2, a curve like c, Fig. 6, being obtained for the combined arrangement.

While it is possible to obtain simultaneous compensation of amplitude and phase in the manner described, the two effects can be treated independently. For example, the thermistor may be included for the purpose of phase correction

alone at the lower end of the frequency range of an amplifier, which may not be required to transmit actually to zero frequency.

Although in the accompanying figures triode valves have been shown for simplicity, it will be evident that pentodes or other multi-electrode valves may be used instead, appropriate arrangements being provided in ways well known in the art.

As the thermistors will be affected to some extent by changes in the ambient temperature, it may be necessary to provide means in any well known manner for eliminating or reducing this effect if it should be appreciable.

If, as will frequently be the case, the apparatus incorporating the invention has to deal with signal input voltages which may be positive or negative with reference to the zero condition corresponding to the absence of signals, the arrangements must be such that the temperature reached by the thermistor for zero input should correspond to a suitable operating point of the resistance-temperature characteristic. Such a point will usually, but not necessarily, be the mid-point of the straightest and/or steepest portion of the characteristic. The heating power should preferably be as large as possible compatible with this requirement in order to reduce the effects of changes in the ambient temperature.

What is claimed is:

1. A thermionic valve amplifier including a first stage and a second stage, an indirectly heated thermistor having a heater and a resistance element, means for connecting the resistance element thereof between the control grid and cathode of said second stage, said means being capable of passing direct current, a source of D. C. voltage included in said connecting means, and means for connecting the heating coil of said thermistor in series with the anode circuit of the first stage, whereby currents of substantially zero frequency may be amplified.

2. A thermionic valve amplifier according to claim 1, also including an additional frequency discriminating couple circuit for connecting the plate of the first stage to the control grid of the second stage.

3. A thermionic valve amplifier according to claim 1, in which the thermistor resistance element is connected in series between the control grid and the negative terminal of the bias source, and another resistance is provided connected between the control grid of the second stage and the positive terminal of said source.

4. A thermionic valve amplifier including a first stage and a second stage, an indirectly heated thermistor including a heater and a resistance element, means for connecting said resistance element thereof to the control grid of said second stage, said means being capable of passing direct current, and means for connecting the heating coil of said thermistor in series with the anode circuit of the first stage, said amplifier including a source of grid bias potential for said second stage, a resistance connected between the control grid of the second stage and the positive terminal of said source, and a connection including a resistance placing said thermistor resistance element in series between said control grid and the positive terminal of said source, also including a second indirectly heated thermistor having a heater and a resistance element, means for connecting said resistance element of said second thermistor in series between the negative

terminal of said source and the resistance element of said first thermistor, and means for connecting the heating coil of said second thermistor also in series with the anode circuit of said first stage.

5. A thermionic amplifier of two stages, including a coupling thermistor of the indirectly heated type having a resistor and a heater, connections placing said heater in the anode circuit of said first stage, a connection from one terminal of said thermistor resistor to the grid of said second stage, a grid resistance connected between said grid and cathode of said second stage and a bias battery connected between said cathode and the other terminal of said thermistor resistor, whereby said thermistor resistor and said grid resistance constitute a bias potentiometer for said second stage.

6. A thermionic amplifier of two stages, including a coupling thermistor of the indirectly heated type having a resistor and a heater, a source of bias potential for the second stage of said amplifier, connections placing said heater in the anode circuit of said first stage, a connection from one terminal of said thermistor resistor to the grid of said second stage, a connection from the other terminal of said resistor to the negative terminal of said bias source, and a grid resistor connected between the positive terminal of said bias source and the control grid of said second stage.

7. A two-stage amplifier including a coupling thermistor having a heater and a resistor, a source of anode potential, a first potentiometer across said source, a connection from the cathode of the first stage to a tap upon said potentiometer, a second potentiometer across said source, a connection from the cathode of the second stage to a tap on said potentiometer, connections placing said heater in series with the anode of the first

stage, a fixed resistor, connections placing said fixed resistor and said thermistor resistor in series between said second cathode and the negative terminal of said source, and a connection from the junction point of said fixed resistor and said thermistor resistor to the control grid of the second stage.

8. An amplifier according to claim 1, additionally including frequency - discriminating coupling means connected between the anode of said first stage and the control grid of said second stage, whereby the rising amplitude-frequency characteristic of one coupling offsets the falling characteristic of the other coupling, so as to obtain substantially uniform amplification over a wide range of frequencies.

9. An amplifier of two stages, including frequency-discriminating coupling means connected from the output of the first to the input of the second stage, a thermistor provided with a heater and a resistor, said heater being coupled in the anode circuit of the first stage, a potentiometer from grid to cathode of the second stage, a bias battery, and connections placing said thermistor resistor and said bias battery in series between a tap on said potentiometer and said cathode.
